His Attorney.

UNITED STATES PATENT OFFICE

169,046

RING BOX OR SIMILAR ARTICLE

John L. Nessler, Pittsfield, Mass., assignor to
General Electric Company, a corporation of
New York

Application April 19, 1952, Serial No. 19,399

Term of patent 14 years

(Cl. D80—5)

To all whom it may concern:

Be it known that I, John L. Nessler, a citizen of the United States, residing at Pittsfield, in the county of Berkshire, Commonwealth of Massachusetts, have invented a new, original, and ornamental Design for a Ring Box or Similar Article, of which the following is a specification, reference being had to the accompanying drawing, forming a part thereof.

In the drawing:

Fig. 1 is a front perspective view of a ring box or similar article showing my new design;

Fig. 2 is an end elevational view; and

Fig. 3 is a rear elevational view.

I claim:

The ornamental design for a ring box or similar article, as shown.

JOHN L. NESSLER.
